UNITED STATES PATENT OFFICE

WILLIAM H. PRATT, OF LYNN, MASSACHUSETTS, ASSIGNOR TO GENERAL ELECTRIC COMPANY, A CORPORATION OF NEW YORK

CENTRALIZED METER RECORDING

Application filed August 12, 1930. Serial No. 474,746.

My invention relates to a system and apparatus for recording at a central station the indication of a meter at a remote point. More particularly my invention relates to the recording at the central station of the indication of the meters of a number of customers scattered over the area served by a public service company, by the temporary use of the several customers' telephone lines. My invention may be applied to any type of customers' indicating or integrating meters such as the customary integrating gas meters, water meters, electric watt-hour meters, etc.

The expense and inconvenience incident to the reading of customers' meters by central station employees need only be mentioned in order that the resulting economies and good will of the customers flowing from the application of such apparatus may be appreciated.

It is, therefore, an object of my invention to provide apparatus by means of which a customer's meter of any of the above or similar types may be recorded directly at the central station without the necessity of employing meter readers.

It is a further object of my invention to provide apparatus for transmitting the indication of a customer's meter directly to the central station by the temporary use of the customer's telephone lines without the aid of any independent connections between the two points.

Another object of my invention is to provide means for recording the reading of any number of customers' meters by the use of the customers' telephone lines in cases where a number of customers are located upon the same party telephone line.

Still other and further objects of my invention will be apparent from the following description taken in connection with the drawings and will be pointed out with more particularity in the claims appended hereto.

In describing the apparatus and its principles of operation which I consider at present to be the best embodiment thereof I have illustrated its application to the recording at a central station of the indication of a customer's electrical watt-hour meter, but it is to be clearly understood that my apparatus

is in no wise limited to this application, but may be applied to any type of a meter either integrating or indicating.

Referring now to the drawings in which the same reference numerals apply to the same elements in each of the several figures. Fig. 1 illustrates in schematic form the several pieces of apparatus which go to make up my meter recording system; Fig. 2 is a plan view, partly in section, of the meter contact making mechanism; Figs. 3 and 4 are perspective views of details of the mechanism; the manner of operation of the contact mechanism is illustrated in Figs. 10 and 11. Fig. 5 is a plan view of the assembly of the resonant relay, distributor and contact making drum, of which Fig. 6 is an elevation; Fig. 7 is a plan view, partly diagrammatic, of the recorder mechanism, of which a portion is shown in elevation in Fig. 8, and Fig. 9 is a perspective view of a zero-stop motor latch which may be applied to my invention.

A general outline of the operation of my system will be best understood by reference to Fig. 1 which is a diagrammatic illustration of the complete system. The operation of the system is initiated by momentarily closing master switch 11 which connects one of the alternating current supply lines 10 to ground and the other to one of the customer's telephone lines and to one side of the tuned relay 13. The supply lines 10 are adapted to be energized from any source of alternating current supply, well known in the art, which will generate a current of any of a number of desired frequencies. Located in the customer's station is an electro responsive device comprising a tuned relay 12 similar to the tuned relay 13 in the central station and when it is desired to record the reading of this particular customer's meter an alternating current is impressed upon the supply lines 10 of a frequency for which the relays 12 and 13 are tuned.

The two relays 12 and 13, when properly energized, serve to start the apparatus in both the customer's station and the central station. The operation of the apparatus in the two stations is effected by the self-starting synchronous motors 16 and 17, respectively,

which are exactly similar. Motors of this type are well known in the art and may be, for example, of the type disclosed in United States Patent No. 1,546,269 to Warren, July 14, 1925. In circuit with the motors 16 and 17 are the contact drums 14 and 15, respectively. Normally, the contact arms of these two drums engage insulated portions of their drums but when actuated by their cooperating relays 12 and 13, the contact arms are moved to conducting segments and the circuits through the motors 16 and 17 are simultaneously completed. These motors are supplied from the standard commercial frequency alternating current supply lines 23 and 24, which are energized from the same or synchronized central stations.

Operation of motor 16 which is operated independently of the meter serves to rotate the distributor 18 and contact making gears 19, of which one is provided for each meter dial. Each of the contact making gears 19 carries a pawl which engages a contact making member positioned in accordance with the meter indication associated with each meter dial pointer. The distributor 18 is geared to rotate at a speed which is a fraction of that of the contact making gears 19 dependent upon the number of dials of the meter. In the example illustrated, which is the usual four dial meter, the distributor rotates at one-fourth the speed of the gears 19. Thus, it will be noted that the distributor 18 places the contact members of the meter dials successively in circuit after each complete revolution of the gears 19. As a result, a contact is made by the several contact making gears at the instant at which the contact making pawl engages the contact element of the respective meter dial pointers which is, of course, dependent upon the angular position, that is, the reading, of the respective meter dials. The effect of these series of contacts is to momentarily short-circuit the customer's telephone lines each time a contact is made.

Turning now to the apparatus located at the central station, there is provided a recording means or instrument 20, which is driven by means of the synchronous motor 17. The rotating arm of this recorder is so geared that it rotates synchronously with the distributor 18. The arms of the rotating recorder are provided with dial identifying markers numbered consecutively 1, 2, 3 and 4 corresponding to the numbers of the dials on the customer's meter. When a contact is made at the customer's meter the effect of the short-circuit of the telephone lines is amplified by means of an amplifier 21 of any type well known in the art, the output of which is used to energize the electromagnet 25. Each of the arms of the rotating recorder is provided with an armature which cooperates

with the electromagnet 25 so that when an impulse is given the electromagnet, due to the contact of a customer's meter, the particular position varying arm which is at that instant travelling above the electromagnet 70 is momentarily depressed and the numeral carried by that particular arm marks an impression upon the travelling recording strip. This strip is divided longitudinally by eleven reference lines corresponding to the digits of the several meter dials. Since this recording arm is synchronized with the contact making apparatus the position in its travel across the recording chart at which an impression is made is dependent upon the angular position of the contact making gears 19 at which contact is made, which, in turn, is dependent upon the reading of the meter. Thus, there is obtained at the central station a record of the reading of each of the several 80 dials of the customer's meter. Such apparatus may be duplicated at each customer's meter although it is obvious that the recording apparatus will serve for any number of customers' meters. Thus, in Fig. 1, I have indicated at 12' a second relay, assumed to be of lower inductance than relay 12, connected to the left-hand wire of the telephone circuit 22 through a condenser, which relay will perform the same function as relay 12, 90 but with respect to another meter and associated apparatus similar to that shown, when a higher selected frequency is impressed on the telephone circuit, and to which frequency the high inductance relay 12 does not respond. For instance, if a low frequency of F cycles be impressed, relay 12 will respond, but the condenser in the circuit of relay 12' prevents sufficient current flowing to operate the last mentioned relay. Now, if a frequency of F+X cycles be impressed on the selective relay circuit, then the high inductance relay 12 does not respond, but the higher frequency current readily flows through the condenser circuit to operate the 100 lower inductance relay 12'. The recording electromagnet 25 and the relay 13 of the recording mechanism will then be designed to respond to either of the selected frequencies, and the operator will be able to read either 110 meter at will by simply changing the frequency impressed upon the selective relay circuit. A variable speed direct current motor driving a synchronous generator is indicated in the lower right-hand portion of Fig. 1 for supplying the different frequencies to the frequency-responsive relay circuit when switch 11 is closed.

For a better understanding of the details of operation of the contact mechanism attached to a meter whose indications are to be recorded, reference is had to Figs. 2, 3 and 4. Referring more particularly to Fig. 2, the four customary dials of a commercial type watt-hour meter are indicated at 30, 31, 120 125 130

32, and 33; the dial 33 representing the units dial and the others, the successively larger multiple dials. The indicating pointers cooperating with these dials are illustrated as 5 being actuated in the usual manner by the meter disc (not shown) through the main driving gear 34 and the ratio gearing 35. Attached to the spindles of the several dials are the contact arms 36.

10 As shown more clearly in Fig. 3, these contact arms comprise a hub portion 37 provided with a set screw 46 by means of which an arm is secured to its respective spindle. The contact arm consists of a flat elongated 15 strip the outer end of which is bent at substantially right angles to the main axis of the strip and parallel to its axis of rotation. This outer end is provided with a projecting tongue 39 pressed out near the center of 20 one side. Pivotally mounted on this end portion is a fiber contact operating member 38 of an irregular outline which is clearly illustrated in the drawings. It is provided with a recess 47 which loosely engages the 25 tongue 39. Extending over the range of all of the several contact arms are thin flexible contact plates 44. Associated with each meter dial and cooperating with the corresponding 30 contact plate is a circular contact disc, the periphery of which is somewhat upturned. Also associated with each meter dial is the contact operating gear 19 shown more clearly in Fig. 4. This gear is provided with a flexible wire pawl 40 fixed to the body of 35 the gear at one end in any convenient manner as by the drop of solder 45. The other end of this flexible pawl rests in a small cradle 41 secured to the gear. The result is that the outer end of the pawl 41 acts to effect 40 a driving engagement when the rotation of the gear is in the one direction but when the rotation is in the opposite direction the flexibility of the pawl permits it to spring past any driving engagement.

45 In the operation of this contact making mechanism, the contact actuating gears 19 are driven by the synchronous motor 16 as shown in Fig. 1. The outer end of the wire pawl mounted on each gear is adapted to engage 50 the projection 48 of the fiber plate 38, mounted to pivot freely on the outer end of the contact arm 36. The contact arm 36 is secured to the meter dial spindle and assumes a 55 position corresponding to that of the dial pointer, that is, it gives an indication of the reading of the corresponding dial. Upon the rotation of the gears 19, when the pawl 40 engages the projection 48 of the fiber plate 38, 60 this plate is slightly rotated about its pivot 42 and the resultant angularity of the side of the plate 38 which engages the corresponding contact plate 44 presses this plate 44 into engagement with the corresponding contact 65 disc 43. Fig. 10 illustrates the position of

the parts as a pawl 40 approaches a contact device before plate 44 is pressed against disc 43, and Fig. 11 illustrates the parts as a contact making operation is made and the position of pawl 40 just before it slips past projection 48. Ordinarily two of the gears 19 will rotate in a clockwise direction and the other two in a counter clockwise direction. The saddle 41 will be on the driving side of pawl 40 in either case. As indicated by the arrow adjacent thereto the gear 19 illustrated in Figs. 10 and 11 is shown as operating in a clockwise direction as viewed from the front of Fig. 2. As shown in the connections illustrated in Fig. 1 this results in a momentary short circuiting of the customers' telephone lines to effect an impulse at the central station. As explained below these gears are adapted to make four complete revolutions, one for each of the meter dials, and by means of the distributor 18 the contact discs 43 are successively placed in circuit.

In the preferred embodiment of my invention I mount the rotary distributor 18 and the contact drum 14 on the same shaft as illustrated in Figs. 5 and 6, and assemble them together with the tuned relay 12 into a unitary structure. The tuned relay 12 comprises a U shaped magnetic core 50 provided with the energizing winding 70. One of the legs 55 of the U shaped core 50 is provided with a pole piece 51 and bridging the gap between the two legs of the U is the vibrating magnetic reed 52, secured to the other leg of the U by means of the clamping member 71. The outer end of the vibrating reed 52 engages a projection 72 on the contact arm 53 which is resiliently mounted at 54. The contact arm 53 is provided with the contact 55 which cooperates with the insulated segment 57 and the conducting segment 56 of the contact drum 14. This contact drum is driven from the synchronous motor 16 through the main driving gear 60 and the cam ring 59. The insulated segment 57 is provided with a tongue 58 projecting into a recess in the conducting segment 56. The contact drum 14 is mounted upon the shaft 69 upon which is also secured the rotating contact brush 74 of the distributor 18. In the preferred embodiment of my invention this distributor 18 comprises the conducting segments 61, 62, 63 and 64 which terminate in the conducting spools 65, 66, 67 and 68, the whole being secured to a stationary piece of insulating material 73. The object of these conducting spools at the end of the contact segments is to maintain engagement with the contact brush 74 until it is bent sufficiently to snap quickly into engagement with the next contact segment. In this way there is no appreciable interval of time during which contact is not made with any of the contact segments.

As stated above when the apparatus is at 130

rest the contact 55 engages the projection 58 of the insulated segment 57 of the contact drum 14. When an impulse of the proper frequency is received by the resonant relay 12 as described in the outline of operation of the system, the reed 52 will vibrate in resonance and move the contact arm 53 until the contact 55 engages the conducting segment 56 of the contact drum. This completes the circuit to the synchronous motor 16 as described above and the contact drum together with the distributor will rotate through one complete revolution until the contact 55 again engages the insulating projection 58, when the motor circuit is broken and the apparatus comes to rest. In the operation of this apparatus the switch 11, Fig. 1, for starting the motor is intended to be closed only momentarily. The switch 11 should be closed long enough to cause the contact 55, Fig. 5, to be moved from the offset insulating segment 58 to the conducting portion 56, but the switch should be opened again before segment 56 makes a complete revolution unless it be desired to repeat the recording operation. After reed 52 stops vibrating it leaves contact 55 on the conducting segment 56 which starts the synchronous motor 17, and cam member 59 is provided to move contact 55 back again to its initial position during the latter part of a revolution of segment 56. Thus, just before the contact 55 comes opposite the offset insulating segment 58 it is moved by cam member 59 so that it will ride upon the insulating portion 58 and open the motor circuit.

The apparatus for recording at the central station the readings of the various customers' meters is illustrated in more detail in Figs. 7 and 8. This apparatus consists of a rotatably mounted platform 80 which carries the pivotally mounted recording arms 81, 82, 83 and 84. This rotating platform is driven by the synchronous motor 17 through the intermediate gearing 90. On the lower end of the platform spindle 91 is mounted the contact drum 15 which is identical with the contact drum 14 described in detail above. The synchronous motors 16 and 17 being in synchronism cause the contact drums 14 and 15 and the distributor 18 and recorder 20, all to be rotated in synchronism. On the outer end of each of the recording arms 81-84 is provided a magnetic armature 85, somewhat arcuate in form, and centrally disposed on the underside of each of these armatures is mounted the marker 86. These markers carry the numerals 1, 2, 3, and 4 for the recording arms 81-84 respectively and correspond to the several dials of the customer's meter. Mounted directly beneath the path of the armatures 85 is the U shaped magnet 25 provided with energizing windings 92, and the arcuate pole members 87. A record chart 88 passes over the winding drums 89, mount-

ed in any convenient manner, and between the faces of the magnetic poles 87 and the path of the magnetic armatures 85. This record chart is longitudinally marked by eleven equally spaced lines marked from zero to 10 inclusive and corresponding to the respective digits of the meter dials. 70

Assume that the units dial 33 of Fig. 2 has an indication of 5 when the contact arm 36 is engaged by its corresponding actuating gear 19 and an impulse is sent out from the customer's station. When the dial reads 5 this impulse will occur at the end of approximately a half revolution of the gear 19. During the same interval of time the contact arm 81 will have moved half-way across the recording chart 88 and at the instant the impulse is received, the magnetic armature 85 is drawn down by the electromagnet 25 and the marker 86 imprints the numeral 1 upon the longitudinal ruling marked 5. Similarly each of the successive recording arms 82, 83 and 84 will print a record on the chart corresponding to the reading of the respective dial of the customer's meter. If desired, arcuate rulings may also be made upon the record chart to facilitate in identifying the corresponding readings of the several dials of a single customer. For example the reading indicated on the arcuate ruling 93 indicates a meter reading of 4627 and that on the arcuate ruling 94 representing a reading of a second meter is 4486. 85

In order to prevent the synchronous motors 16 and 17 from coasting when they are deenergized and to insure that they will both stop in the same position in readiness to perform another meter recording operation I have found it advantageous to use a stop latch, such, for example, as is illustrated in Fig. 9 of the drawings. In the preferred embodiment of this device the motor core member 100 is provided with polar projections 105, 106 which shunt the main magnetic gap in which is mounted the motor armature. Bridging these two polar projections is a resilient magnetic strip 107, secured to the pole 105 by means of the screws 111 and normally resting against the adjusting screw 109 which is mounted on a member 108 supported from the pole 106. This strip 107 is provided with an outturned flange 112 in which is cut the recess 110^a. Fixed to the driving pinion 104 of the motor and rotating therewith is an arm 110. When the coil 101 of the synchronous motor 16 is energized, the armature 107 is attracted to the polar projection 106, withdrawing the flange 112, and the arm 110 is free to rotate unobstructed; but upon deenergization of the motor the arm 107 springs back against the stop 109 and the tapered flange 112 enters the path of the moving arm 110 which drops in the recess 110^a and latches the motor in this zero position. Although this feature is not ab- 120 125 130

solutely essential to my invention I have found that by the use of such a latch it is possible to accurately stop each of the motors at the zero position simultaneously and to insure that they are always maintained in exact synchronism.

It is believed that from the foregoing outline of operation of this system as a whole and from the detailed description of the operation of the several component parts that the detailed operation of this system as a whole will be readily understood.

While I have described with particularity the structures and arrangements which I consider at present to be the best embodiment of my invention I do not wish to be limited thereto but I aim to cover in the following claims all those modifications and variations within the true spirit and scope of my invention.

What I claim as new and desire to secure by Letters Patent of the United States is:

1. A system for recording at a central station the indication of an integrating meter having a plurality of dials, comprising contacts and a contact actuating device, positioned in accordance with the dial indication associated with each of said dials, an independently driven mechanism for operating said devices, an electro-responsive device located at the central station, a circuit connecting said contacts and said electro-responsive device, recording means including recording elements corresponding to each of said dials successively actuated by said electro-responsive device, and means for synchronizing said mechanism and said recording means whereby the time of actuation of each recording element is dependent upon the indication of its corresponding dial.

2. A system for recording at a central station the indication of an integrating meter having a plurality of dials comprising contacts and a contact actuating device positioned in accordance with the dial indication associated with each of said dials, a mechanism for operating said devices driven independently of said meter, a circuit extending from the contacts associated with the dials of said meter to the central station, distributing means for successively connecting the contacts associated with said dials in said circuit, an electro-responsive device located at the central station and connected in said circuit, dial identifying recording means actuated by said electro-responsive device, and means for synchronizing said driving mechanism, said distributing means and said recording means.

3. A system for recording at a local station the indication of a meter at a remote point, comprising contacts and a contact actuating device positioned in accordance with the meter indication associated with said meter, mechanism for operating said device,

a synchronous motor for driving said mechanism, an electro-responsive device located at the central station, a circuit connecting said contacts and said electro-responsive device, movable recording means actuated by said electro-responsive device, a synchronous motor for driving said recording means, and means for supplying synchronized alternating currents to the synchronous motors at the local and remote points.

4. A system for recording at a central station, the indication of a customer's meter by the use of the customers' telephone lines, comprising contacts and a contact actuating device positioned in accordance with the meter indication associated with said meter, a connection between said contacts and the customers' telephone lines whereby the latter are adapted to be short-circuited by engagement of said contacts, driving mechanism for said device, an electroresponsive device located at the central station and in circuit with said telephone lines, movable recording means controlled by said electro-responsive device and means for synchronizing said mechanism and said recording means.

5. A system for recording at a central station the indication of an integrating meter having a plurality of dials, comprising contacts and a contact actuating device positioned in accordance with its dial indication associated with each of said dials, a synchronous motor for driving said devices, a circuit comprising the customers' telephone lines extending from said meter to said central station, distributing means for successively connecting the contacts associated with said dials in said circuit and electro-responsive device located at the central station and connected in said circuit, movable recording means including a plurality of recording elements corresponding to the several dials, successively actuated by said electro-responsive device, a synchronous motor for driving said recording means, and means for supplying synchronized alternating currents to said motors at the local and remote points.

6. A system for recording at a central station the indication of a meter at a remote point, comprising a contact making device positioned in accordance with the meter indication associated with said meter, a synchronous motor driven mechanism for actuating said device, an electro-responsive device located at the central station, a circuit connecting said devices, recording means actuated by said electro-responsive device, a second synchronous motor for moving said recording device into recording position, a common source of supply for said synchronous motors, and means for starting and stopping said motors simultaneously.

7. A system for recording at a central station the indication of a meter at a remote point, comprising contact mechanism having

a definite cycle of operation associated with said meter, synchronous motor driven means for driving said mechanism, an electro-responsive device located at the central station, 5 a circuit connecting said contact-mechanism and said device, recording means actuated by said electro-responsive device, a second synchronous motor for moving said recording means to recording position, means for simultaneously initiating operation of said synchronous motors, a common source of supply 10 for said motors, and means for stopping operation of said two synchronous motors after the completion of a single cycle of said contact mechanism.

8. A system for recording at a central station the indication of a meter at a remote point, comprising contact mechanism associated with said meter, synchronous motor 20 driving means for said mechanism, an electro-responsive device located at the central station, a circuit connecting said contact mechanism and said electro-responsive device, recording means actuated by said electro-responsive device, a second synchronous motor for moving said recording means to recording position, a common source of supply for said synchronous motors, latch means associated with each synchronous motor to insure 25 their stopping at predetermined points, and means for releasing said latch means simultaneously to initiate a meter recording operation.

9. A system for recording at a central station the indication of a remote customer's integrating meter having a plurality of dials comprising contacts and a contact actuating device associated with each of said dials, a synchronous motor for driving said devices, a circuit comprising the customers' telephone lines extending from said meter to said central station, distributing means for successively connecting the contacts associated with said dials in said circuit whereby said 40 lines are adapted to be short-circuited by engagement of said contacts, an electro-responsive device located at the central station and connected in said circuit, recording means including a plurality of recording elements corresponding to the several dials successively actuated by said electro-responsive device, a synchronous motor for driving said recording means, means for supplying synchronized alternating currents to said motors 45 at the local and remote points, means for simultaneously initiating operation of said motors, means for de-energizing said motors after a complete cycle of operation of said distributing means, and latch means associated with each of said motors to insure their stopping at predetermined points upon their de-energization.

10. A system for selectively recording at a central station the indication of a plurality 60 of customers' meters located at remote points.

comprising contacts and a contact actuating device associated with each of said meters, mechanism driven independently of said meters for actuating said devices, electrical devices responsive to different frequencies of 70 periodically varying currents for initiating the operation of the several mechanisms, a single circuit connecting said electrical devices, means for supplying to said circuit periodically varying currents of any of the 75 several frequencies to which said electrical devices are responsive, an electro-responsive device located at the central station, a connection between said contacts and said electro-responsive device, recording means actuated by said electro-responsive device, and means for synchronizing a selected mechanism with said recording means.

11. A system for selectively recording at a central station the indication of a plurality of customers' meters located at remote points, comprising contacts and a contact actuating device associated with each of said meters, mechanisms driven independently of said meters for actuating said devices, resonant 90 relays tuned to different frequencies of alternating currents associated with the several meters, a single circuit connecting said relays, means for supplying to said circuit alternating currents of any of the several frequencies to which said relays are tuned, contact devices controlled by the several relays, each adapted upon actuation to initiate the 95 operation of its corresponding actuating mechanism, an electro-responsive device located at the central station, a circuit connection between said contacts and said electro-responsive device, recording means actuated by said electro-responsive device, and means for synchronizing a selected actuating mechanism with said recording means.

12. In an apparatus for recording at a central station the indication of a dial type meter at a remote point, a contact mechanism for said meter comprising a contact disc and a contact plate associated with the dial of said meter, a contact arm rotated with the meter pointer, means associated with said contact arm for actuating said plate and disc into engagement, and independently driven means adapted, during operation, to operate said actuating means at a point dependent upon the position of the meter pointer.

13. In an apparatus for recording at a central station the indication of a dial type meter at a remote point, comprising cooperating contacts associated with the dial of said meter, a contact arm rigidly secured to the spindle of the meter pointer in the same radial plane as said pointer, contact actuating means associated with said arm, and independently driven means adapted, during operation, to control said actuating means to close said contacts at a point dependent upon the position of said meter pointer.

14. In an apparatus for recording at a central station the indication of a meter at a remote point, said meter including the usual dial and pointer, a contact mechanism for said meter comprising cooperating contacts associated with said dial, a rotatable contact arm the outer end of which is bent parallel to its axis of rotation, rotated with said pointer, contact actuating means comprising an irregular shaped plate of insulation material freely pivoted on the outer end portion of said arm, and independently driven means adapted, during operation to engage and turn said plate on its pivot to close said contacts at a point dependent upon the position of said meter pointer.

15. In an apparatus for recording at a central station the indication of a meter at a remote point, said meter including the usual dial and pointer, a contact mechanism for said meter comprising cooperating contacts associated with the dial of said meter, a contact arm moved with the meter pointer, contact actuating means associated with said arm, and an independently driven gear provided with a spring pawl adapted to engage said contact actuating means to close said contacts at a point dependent upon the position of the meter pointer.

16. In an apparatus for recording at a central station the indication of a dial type meter at a remote point, a contact mechanism for said meter comprising a contact disc and a contact plate associated with the dial of said meter, a rotatable contact arm, the outer end of which is bent parallel to its axis of rotation, rigidly secured to the spindle of the meter pointer in the same radial plane as said pointer, contact actuating means comprising an irregular shaped plate of insulation material freely pivoted on the outer portion of said arm, and an independently driven gear provided with a spring pawl adapted to engage said plate and turn it on its pivot to close said contacts at a point dependent upon the position of the meter pointer.

17. In an apparatus for recording at a central station the indication of a multi-dial meter at a remote point, said meter including the usual dials and cooperating pointers, a contact mechanism for said meter comprising cooperating contacts associated with each of the several dials, contact arms rotated with the several pointers, contact actuating means associated with each arm, and independently driven means adapted, during operation, to control the several actuating means to close each of said contacts at a point dependent upon the position of their corresponding pointers.

18. In a system for recording at a central station the indication of a multi-dial meter at a remote point, said meter including the usual dials and cooperating pointers, an indication transmitting means comprising co-

operating contacts associated with each of said dials, independently driven contact operating mechanism associated with each of said dials, a signaling circuit, and a distributor having a driving connection common to 70 said contact operating mechanism by means of which said distributor is driven at a speed which is a fraction of that of said mechanism depending upon the number of meter dials, and connections between said distributor and the several contacts whereby the several contacts are successively connected in 75 said signaling circuit.

19. In a system for recording at a central station the indication of a meter at a remote 80 point, comprising in combination with such meter, recording means comprising a continuously moving recording element, a record chart positioned adjacent to the path of movement of said recording element, an electro-responsive device energized in response to the indication of said meter, and a magnetic member carried by said recording element 85 and actuated by said electro-responsive device to cause said element to record an indication upon the chart when in a position with respect to the chart corresponding to the meter indication.

20. In a system for recording at a central station the indication of a meter at a remote 90 point, comprising in combination with such meter, recording means comprising a rotating recording element pivoted about an axis perpendicular to its axis of rotation and provided with a magnetic armature, a record chart graduated in meter indicating units and positioned adjacent to the path of movement of the recording element, an electro-responsive device energized in response to the indication of said meter and adapted to depress 95 said element and armature upon energization.

21. In a system for recording at a central station the indication of a meter at a remote 100 point, comprising in combination with such meter, recording means comprising a continuously moving recording element provided with a magnetic armature, a record chart positioned adjacent to the path of movement 105 of the recording element, and an electro-responsive device including a magnetic core member and an elongated pole piece mounted in proximity to and conforming substantially to, the path of movement of said magnetic armature, said electro-responsive device being energized in response to the indication of 110 said meter to actuate said armature.

22. In a system for recording at a central station the indication of a meter at a remote 115 point, comprising in combination with such meter, recording means comprising a continuously rotating recording element provided with a magnetic armature, a record chart graduated transversely in meter indicating 120 units, and an electro-responsive device in- 125 130

cluding a U-shaped core member substantially arcuate in section and provided with arcuate elongated pole pieces extending substantially across the width of the record chart and 5 located in proximity to the path of said magnetic armature said electro-responsive device being energized in response to the indication of said meter to actuate said armature.

23. In a system for recording at a central 10 station the indication of a multi-dial meter located at a remote point, comprising in combination with a meter having a plurality of dials, recording means comprising a rotatable platform provided with a plurality of 15 recording elements, one element for each of said dials, a record chart graduated transversely in meter indicating units and positioned adjacent to the path of movement of said recording elements with its graduation 20 lines transverse to the direction of movement of the recording elements, an electro-responsive device energized successively in response to the indications of the several dials, and magnetic armatures carried by the 25 several recording elements and successively actuated by said electro-responsive device.

In witness whereof I have hereunto set my hand this 7th day of August, 1930.

WILLIAM H. PRATT.
